CLAIM

What is claimed is the ornamental design for a male dual lumen bayonet connector, substantially as shown and described.

DESCRIPTION

FIG. 1 is a front isometric view taken from the top, left side of a male dual lumen bayonet connector.

FIG. 2 is a rear isometric view of the male dual lumen bayonet connector of FIG. 1, taken from the top, right side.

FIG. 3 is a front elevation view of the male dual lumen bayonet connector of FIG. 1.

FIG. 4 is a bottom plan view of the male dual lumen bayonet connector of FIG. 1.

FIG. 5 is a rear elevation view of the male dual lumen bayonet connector of FIG. 1.

FIG. 6 is a left side elevation view of the male dual lumen bayonet connector of FIG. 1.

FIG. 7 is a right side elevation view of the male dual lumen bayonet connector of FIG. 1; and,

FIG. 8 is a top plan view of the male dual lumen bayonet connector of FIG. 1.

The broken lines shown in the drawings are for illustrative purposes only and form no part of the claimed design.
